Union, N. J.

Application February 24, 1936, Serial No. 65,284

10 Claims. (Cl. 225—1)

This invention relates to an apparatus for cooling and dispensing liquid and relates more particularly to a system for dispensing gas containing liquids forced through a conduit under pressure.

An object of the invention is to provide a cooling apparatus in which the cooling tanks during operation are completely sealed against the entrance of air.

10 Another object of the invention is to provide a cooling apparatus including a plurality of containers which may be filled successively and in which the gases from one container are caused to flow into another container.

15 Another object of the invention is to provide an apparatus in which a plurality of containers or cooling tanks are connected by conduits for the flow of liquid from one tank to another and in which gases accumulating in a partly filled

20 tank are caused to flow into an adjacent tank under the action of flowing liquid.

Another object of the invention is to provide an apparatus for cooling and dispensing gas containing liquid such as beer wherein automatic 25 indication is given when the source of supply, as for example, the keg, is empty.

Another object of the invention is to provide a beer cooling and dispensing apparatus in which a new source of supply may be connected without 30 the necessity of emptying the cooling tanks.

Various systems have been made for cooling and dispensing gas containing liquids such as beer, and it is common practice to use a plurality of cooling vessels or tanks surrounded by a 35 cooling coil or by a cooling medium such as ice or mechanical refrigeration. It is also known that when connecting these tanks to a keg and applying pressure to the liquid in the keg (as is the practice) that the liquid is forced into the 40 first tank and when this tank has partly filled and the released and initial gases have been compressed at the top of the tank, the incoming liquid is prevented from filling the tank and the liquid starts to flow into the next tank through 45 a conduit as provided.

Various means have been employed for relieving the partly filled tank of gas which means have in some cases been in the form of automatic valves or hand cocks which may be opened 50 to relieve the pressure and then closed. It has been found that in the case of a hand cock or valve that it is difficult to determine the proper time to open the cock and in the case of automatic valves that they discharge liquid causing a loss of liquid to the user of the system in

which such valves are provided. Furthermore, in the case of automatic valves the pressure is gradually relieved and the keg empties without giving any indication of such conditions to the one dispensing the liquid and the tank or tanks 5 then become empty making it necessary, each time a new keg is connected, to fill the tanks with relatively warm beer which must be cooled before it is dispensed.

Furthermore in systems where it is necessary 10 to empty the tanks each time a new keg is connected, the moist air in the tank is subjected to the cold surface of the tank and freezes in the form of a layer of frost. It has been found that the presence of frost in the tanks results in what 15 is termed "flat" beer, making it necessary in some extreme cases to waste a portion of the beer when a new keg is connected since flat beer is unpalatable.

In the present apparatus the tanks are connected to a keg and as the beer fills the first tank to the point where the pressure prevents the further filling of the tank, the liquid flowing into the next tank acts to operate an ejector in communication with the first tank to cause the gas 20 above the liquid in the first tank to enter the second tank thus permitting the beer flowing from the keg to fill the first tank. Means in the form of an outlet cock are provided for removing excess gas from the last or dispensing tank. The 25 removal of excess gas is only necessary however for the initial filling of the tanks. This means is employed so that the excess gases may be drawn off conveniently without loss of any appreciable amount of liquid. The purposes and advantages 30 of this operation will be more clearly explained hereinafter.

The invention will be more clearly understood by reference to the following description together with the accompanying drawings, in which 40

Fig. 1 is a perspective view of an apparatus embodying the present invention;

Fig. 2 is an enlarged fragmentary view of the tanks shown in Fig. 1 taken in vertical cross section;

Fig. 3 is a top view of the tanks shown in Fig. 2, and

Fig. 4 is an enlarged detail view in cross section showing the upper portion of a tank.

The present invention is shown and described 50 as applied to a dispensing system including a compressor 10, which by means of pipe 11, subjects the beer or other liquid in a keg 12 to a predetermined pressure sufficient to hold beer in what may be considered a solid state, that is, 55

impregnated with the desired gaseous content. In place of a compressor it is practical with the present system to use a tank of CO₂ gas. A pipe 13 leads from the keg to a container or cooling tank 14. When the tank 14 has filled to the highest possible height permissible by gases compressed in the upper portion 15 thereof the beer flows through conduit 16 into the next cooling tank 17.

10 Ordinarily the tank 14 would not fill entirely and the upper portion of tank 17 would also be prevented from filling but the opposing gases in the upper portion of the tanks are, in accordance with the present invention, carried from 15 one tank to another and discharged into the last or dispensing tank by means of gas relief valves in the form of ejectors 20 and 21 having screens 20' and 21'. A screen 22' is also provided in tank 17 to collect any sediment or 20 foreign matter.

Although only two tanks are shown it is obvious that a greater number of such tanks may be employed. The tanks are disposed in a refrigerator 22 containing a cooling medium such as ice or mechanical refrigeration to bring the beer to a desired low temperature. When the beer flows from the keg and enters the tank 14 it is relatively warm and as it flows into the tank an appreciable amount of gas escapes and builds 25 up a pressure in the upper portion of the tank. Some of the gas escapes through the restricted opening 23 leading to the ejector 20. The area of the communicating opening 23 may be varied by means of a hand valve 24' having a stem 24 which may be moved to close the opening entirely or adjusted to control the amount of gas 30 passing into the adjacent tank.

The gas in the upper portion of the tank 14 does not however escape fast enough to permit 40 the liquid to fill the tank and the liquid therefore starts to flow through pipe 16 into tank 17. This flowing liquid travels through portion 25 of pipe 16 in which a tubular extension 26 is disposed. This extension affords communication 45 between the pipe 16 and the restricted opening 23 leading from tank 14. The flowing liquid creates a vacuum in the extension thus accelerating the movement of the gas or foam from the upper portion of tank 14 into the moving liquid 50 in pipe 16 and the gases or foam are thus carried into the tank 17 thus permitting the liquid in tank 14 to reach a high level and fill this tank. It will be understood that by reason of the ejectors the gases pass from one tank to 55 the next and finally when accumulated in the dispensing tank may easily be drawn off. In the present construction the gas from tank 14 accumulates at the top of tank 17 from which it is removed by opening a pet cock in a manner to be 60 later described.

Although liquid flows into the tank 17 the compressed gas in the upper portion of this tank prevents it from being filled entirely. However, because the liquid, prior to flowing into tank 17, 65 has been cooled in tank 14, it is evident that the gas accumulating above the liquid in tank 17 will be considerably less than that above the liquid in tank 14.

As shown the ejector 21 on the tank 17, which 70 tank may be termed the dispensing tank, is similar in its essential construction to the ejector 20 except that ejector 21 has a depending tubular extension 27 which lengthens the constricted outlet 28 which is controlled by a hand valve 29' 75 having a stem 29. A tubular extension 31 is dis-

posed in a conduit 32 leading to a chamber 33 terminating in a hand valve or spout 34. Within the chamber 33 is a cartridge containing a quantity of loose particles to restrict the flow of the beer. This form of construction or means for retarding the rate of flow without changing the pressure is shown and described in copending application of E. G. Hedges, Serial No. 6,853 filed February 16, 1935 and in combination with the gas control of the present invention serves to 10 make possible a desired degree of flow from the nozzle or spout 34 to permit the filling of a receptacle with quiet beer or beer for immediate consumption in which the gases are not unpleasantly active.

When the tanks are filled, at the initial filling, the tank 14 as above mentioned fills completely. In the tank 17 a cushion of gases and foam accumulates leaving the level of the liquid a considerable distance from the lower end of the 20 extension 27. It will be evident that an opening of the nozzle 34 would cause a flow of gas from the top of tank 17 since the gases would enter the depending extension 27 and agitate the beer flowing through the conduit. This excess 25 amount of gas would of course only occur for a short time or until the high pressure gas above the beer had been removed but would necessitate the loss of several glasses of beer. To avoid this loss means are provided in the form of a pet- 30 cock 35 positioned in convenient reach below the spout 34. This pet-cock is connected by pipe 36 to an opening 37 at the top of the dispensing tank 17. When the pet-cock is opened the excess 35 gas escapes carrying a very small quantity of liquid, in fact the discharge is in the form of a heavy foam and the amount of beer lost is extremely small amounting to several ounces.

After the excess gas has been removed the level of the beer in the tank 17 rises filling the tank 40 completely thus cutting off the flow of gas through the outlet 28 and instead a small amount of beer flows through this outlet and into the conduit 32 each time a quantity of beer is drawn. When the excess gas has been removed the pet-cock 45 is closed and it is not necessary to again open this cock unless all the beer has been removed from the tank and a new supply to be let in as when the tanks are emptied for cleaning or re-tapping.

With the present system it is not necessary to 50 empty the tanks as in other systems when a new keg is to be connected.

Heretofore it was impossible to tell when the keg was empty and the user was only aware of this condition when no more beer could be drawn 55 and obviously this meant that both the keg and the tanks were empty. In the present system as soon as the keg is empty and the beer level in the tank 17 drops below the extension 27 the gas is forced through the ejector passage and into 60 the conduit 32. Thus the one dispensing beer upon opening the spout notes the discharge of gas or foam. The spout is immediately closed and valves 38 and 39 at the keg are closed. The keg is disconnected and another keg connected. The 65 beer is then forced into the tanks and after relieving the excess gas by means of pet-cock 35 the system is again ready for use.

It has been found that by reason of the cartridge 33 the conduits may be of relatively large 70 inside diameter. For example, the conduit leading from the bottom of tank 14, for the flow of liquid into tank 17, may be $\frac{3}{8}$ of an inch inside diameter and the conduit leading upwardly from the bottom of tank 17 may be $\frac{1}{4}$ of an inch 75

inside diameter. Thus a quick supply of liquid may be obtained and at the same time by reason of the loose particles in the cartridge 33 the dispensed liquid is delivered at a practical rate of speed and the condition known as "quiet", particularly when dispensing beer, is attained.

The purpose of the small inside diameter of the conduit leading from the tank 17 is to reduce the amount of gas in the conduit and thus minimize the discharge of gas when the faucet is initially opened. Obviously no excessive accumulation of gas will occur after the conduit has once filled with liquid and the liquid is being dispensed.

It is immaterial with my system whether or not the beer in the freshly tapped keg is warm, as for example at a temperature of 60 to 65 degrees F., because after the new keg is connected to the system the beer drawn from the spout comes from the tanks which are full and in which the beer is fully cooled. This is of decided advantage as will be appreciated by those familiar with existing systems.

As heretofore mentioned the tanks are completely sealed from the atmosphere, there being no outlet to the atmosphere therefrom except through the pet-cock 35 and this only when the system is initially filled or re-tapped.

In providing a sealed system the tanks are each provided with a flange 41 and a reinforcing collar 42 which seats on a collar or separator plate 43. This separator plate may include any number of apertures to seat collars 42, the apertures being spaced in accordance with the selected arrangement of the tanks. In the drawings where only two tanks are shown each tank is provided with a cover 44 held in place by a force bolt 45 extending through a threaded aperture at one end of a yoke 46. The yoke is held in place by a tie bolt 47 secured at one end to the collar plate and extending through the yoke a tightening nut is provided to draw the force bolts into firm contact with the covers and these force or pressure bolts may be turned to exert the necessary force to hold the covers tightly against gaskets 48 thus effectively sealing the tanks.

It will be obvious that by reason of the novel construction of the holding means for the covers that all the covers are readily removable by the manipulation of a single bolt when it is necessary to clean out the tanks.

The covers are, however, easily replaced and force necessary to keep them tight against internal pressure may readily be applied by means of the force bolts provided. The interiors of the tanks are therefore easily accessible which offers a considerable advantage.

Although a preferred embodiment of the invention is shown and described herein, it is to be understood that modifications may be made therein without departing from the spirit and scope of the invention as set forth in the appended claims.

What is claimed is:

1. A liquid dispensing apparatus comprising a pair of containers, a source of liquid supply for said containers, a conduit for the flow of liquid from one container to the other container, pressure exerting means for forcing said liquid into said containers, means connected to said containers for drawing liquid therefrom, and means in said conduit operating upon a flow of liquid through said conduit to remove gas above the liquid level in one container for discharge into the other container.

2. A liquid dispensing apparatus comprising a

pair of containers, a source of liquid supply for said containers, a conduit for the flow of liquid from a container to the other container, pressure exerting means for forcing said liquid into said containers, means connected to said containers for drawing liquid therefrom, and an ejector in said conduit for causing gases or foam above the liquid level of one container to be discharged into the other container.

5

3. A liquid dispensing apparatus comprising a plurality of containers, a source of liquid supply for said containers, means providing communication between said containers, means for forcing liquid from said supply into one of said containers and through said first mentioned means into the other container, means connected to said containers for drawing liquid therefrom, and means controlled by liquid flowing through said first mentioned means for causing gases or foam above the level of liquid in one container to flow into an adjacent container.

4. A liquid dispensing apparatus comprising a plurality of containers, a primary source of liquid supply for said containers, conduits for the flow of liquid from one container to another container, means connected to said containers for drawing liquid therefrom, and a by-pass in communication with one container above the liquid level thereof to release accumulated gases from one container to another, and means whereby a drop in the liquid level below a predetermined point in at least one of said containers gives physical indication of the depletion of the liquid at the primary source.

5. A liquid dispensing system comprising a plurality of hermetically sealed tanks, means for conducting liquid from one tank into another, means connected to said tanks for drawing liquid therefrom and a restricted passageway leading from the one tank into said first mentioned means, whereby the gas above the liquid in the one tank is forced into the other tank upon the flow of liquid through said first mentioned means.

6. A liquid dispensing system comprising at least two tanks, means for admitting liquid to one of said tanks, means connecting said tanks to permit the flow of liquid from the one tank into the other, means connected to said tanks for drawing liquid therefrom, means connecting one tank with the other to remove gases from the one tank into the other, and means for accelerating the movement of said gases upon the flow of liquid through said second mentioned means.

7. In a pressure system for dispensing activated liquids, the combination of at least two tanks, one constituting a receiving tank and one a dispensing tank, means for forcing activated liquid under pressure into said receiving tank, means for conducting liquid from said receiving tank into said dispensing tank, means for relieving the pressure of the gases above the liquid in said receiving tank, said means being disposed in such relation to the liquid flowing from the receiving tank to the dispensing tank as to discharge the gases from the receiving tank thereto and also to cause an acceleration of the movement of said gases.

8. A system closed to the atmosphere for dispensing charged liquids, comprising in combination, a plurality of tanks and a source of liquid supply, means for maintaining pressure upon said liquid in said source, means for connecting one of said tanks to said source, means for dispensing liquid from another of said tanks, means

75

interconnecting said tanks in serial relation for the passage of liquid from one tank to another, and means communicating with said last mentioned means to pass gases accumulating above 5 the level of the liquid in one tank into said communicating means.

9. A system closed to the atmosphere for dispensing charged liquids, comprising in combination, a plurality of tanks and a source of liquid 10 supply, means for maintaining pressure upon said liquid in said source, means for connecting one of said tanks to said source, means for dispensing liquid from another of said tanks, and means interconnecting said tanks in serial relation 15 to pass gases accumulating above the level

of the liquid in one tank into the liquid flowing into the next tank in the series.

10. A system closed to the atmosphere for dispensing charged liquids, comprising in combination, a plurality of tanks and a source of liquid supply, means for maintaining pressure upon 5 said liquid in said source, means for connecting one of said tanks to said source, means for dispensing liquid from another of said tanks, conduits connecting said tanks in series, and means 10 in each conduit for discharging gas above the liquid level of one tank into the liquid flowing into another tank.

EDWARD G. HEDGES.
